Primary Examiner — Austin Murphy*(74) Attorney, Agent, or Firm* — Blank Rome LLP(57) **CLAIM**

The ornamental design for a toothbrush case, as shown and described.

DESCRIPTION

FIG. 1 is a perspective view of a toothbrush case of the present design, the toothbrush case comprising a cap and a base.

FIG. 2 is a front view of the toothbrush case of FIG. 1.

FIG. 3 is a rear view of the toothbrush case of FIG. 1.

FIG. 4 is a top view of the toothbrush case of FIG. 1.

FIG. 5 is a bottom view of the toothbrush case of FIG. 1.

FIG. 6 is a right side view of the toothbrush case of FIG. 1, the left side view being a mirror image thereof.

FIG. 7 is a front view of the base of the toothbrush case of FIG. 1 with the cap removed.

FIG. 8 is a rear view of the base of the toothbrush case of FIG. 1 with the cap removed.

FIG. 9 is a top view of the base of the toothbrush case of FIG. 1 with the cap removed.

FIG. 10 is a bottom view of the base of the toothbrush case of FIG. 1 with the cap removed; and,

FIG. 11 is a right side view of the base of the toothbrush case of FIG. 1 with the cap removed, the left side view being a mirror image thereof.
